UNITED STATES PATENT OFFICE

OSCAR BOTO SCHELLBERG, OF NEW YORK, N. Y.

APPARATUS FOR PRACTICE OF DUODENAL DRAINAGE

Application filed February 4, 1929. Serial No. 337,252.

Among the principal objects which the present invention has in view are: to provide an apparatus constructed and arranged for the treatment and irrigation of the intestinal region above the colon; to provide an apparatus of this character wherein the affected regions may be reached by injections of medicated liquids and cultures for the planting of bacteria, by gravitational action; to provide in an apparatus of this character means for siphon drainage of the affected regions and generally to provide a novel and improved apparatus of this character, of a portable and readily adjustable type; and to provide a table for supporting the patient which is so formed that one end thereof will be hinged at a point adjacent the center of the table and arranged to incline downwardly from the center towards its outer end, whereby the medicated liquid gravitates and drains from the body without filling up and accumulating in the stomach.

Drawings

25 Figure 1 is a side elevation of a receiving table constructed in accordance with the principles of the invention and illustrating the approximate position of associated medicament containers, and showing in dotted lines the hinged end of the table in lowered position.

Figure 2 is a section through the table on the line 2-2 of Figure 1.

Figure 3 is a section through another portion of the table on the line 3-3 of Figure 1.

Figure 4 is a top plan view of the control valve and tube connections for admitting or withdrawing liquids to the intestinal regions to be acted upon.

Figure 5 is a side elevation, partly in section, of the mechanism shown in Figure 4.

Figure 6 is a fragmentary section of the top of one of the medicament containers illustrated in Figure 1.

Figure 7 is a bottom plan view of one of the container covers.

Description

50 In the treatment of disorders of the stom-

ach, duodenum, gall bladder and alimentary canal, it is possible by utilizing the present apparatus, to plant bacteria and irrigate the affected regions by the injections of medicated liquids and cultures. However, in order to obtain access to the intestinal tract above the colon, it is necessary to resort to gravitational action and to this end, I have devised an apparatus, one embodiment of which is herewith illustrated for such treatment.

The main feature of my invention is to provide a reclining table 10, with one end hinged so that it may be quickly and readily inclined downwardly and to support a patient face upward with the buttocks resting upon parallel spaced pads 11 on opposite sides of the table at its center so that the head of the patient will be considerably lower than the colonic tract. The table is supported upon standards 12 disposed at the foot and center thereof as disclosed in Figure 1. The forward or torso receiving portion of the table top indicated at 13, is provided with a pad 14 and is hingedly connected by the hinge 15 to the forward end of the central section of the table directly forward of the pads 11. A screw jack 16 operated by a hand wheel 17 is mounted in the forward hollow standard 18 being at its upper end in pivotal connection with the forward end of the section 13 of the table through the link connector 19 whereby upon proper manipulation of the operating wheel 17, the torso section 13 of the table together with its pad 14 may be inclined from a horizontal position as indicated in dotted lines in Figure 1 and retained in the desired adjusted position to incline the torso of the patient in a downward direction whereby the gravitational action can be taken advantage of, substantially dividing the alimentary canal in two sections and leaving the colon and lower intestines in a horizontal position.

A bracket 20 carried by the forward table 95 standard 18 carries a series of horizontal pivotally connected bracket sections 21 which terminate in a section 22 which carries at its upper end a four-way pipe connection 23 having three intake branches 24, 25 and 100

26 extending in one direction and an outlet branch 27 is adapted for attachment through the union 28 with the inlet extension 29 of a cylindrical valve casing 30 having mounted 5 therein a rotary valve plug 31 operated by an upstanding valve handle 32 for rotation within the casing.

Extending radially from the valve casing 30 and in substantially opposite directions 10 are connector tubes 33 and 34 which communicate with the interior of the valve casing and carry a sector 35 extending therebetween over which a pointer 36 attached to the valve plug is adapted to move for indicating various positions of the valve. The body of the valve plug is provided with four radially extending bores 37, 38, 39 and 40 which meet at the center of the plug and which are mutually angled relative to one 20 another so that upon rotation of the valve plug, communication may be established between the extension 29 and either of the conduits 33 and 34 at one time, or between the conduits 33 and 34 at another. The conduit 25 33 has connected to the end thereof a relatively long depending flexible tube having a glass section 41, which is adapted to hang below the lowermost position assumed by the body of a patient upon the table. The other of the conduits 34 is connected with a long flexible tube having a glass section 42, adapted for introduction into the stomach by swallowing as in the ordinary application of a stomach pump.

35 Arranged above the head of the table upon suitable supporting brackets 43 are a plurality of graduated glass containers, in the present instance three in number as shown at 44, 45 and 46. These containers are connected to the pipe extensions 24, 25 and 26 40 of the four way connector 23. The flow of liquid from the containers to the four-way connection 23 is controlled through the medium of the valves 47, 48 and 49, whereby any 45 suitable mixture of the liquids from the containers or any single liquid, may be passed through the valve 30.

Each of the containers, as best illustrated in Figures 6 and 7 is equipped with a flared 50 top closed by a circular flanged cover plate 50 to the under face of which is attached a plurality of spring clamping fingers 51 whereby the cover plate is securely held over the top of the container. The cover plate is 55 centrally apertured to receive therethrough an electric light bulb 52 extending from a switch socket 53 supported on the plate, whereby the light is utilized to enable clear reading of the graduations upon the container and the heat of the lamp is utilized 60 for heating the liquid contained therein. Suspended from the under face of the cover plate 50 is a thermometer 53 and extending through the cover plate at one side of the lamp socket is a funnel 55 through which the

containers may be filled from time to time.

Supported underneath the center of the table 10 beneath the pads 11 is a drainage pan 56 emptying into a receptacle 57 supported upon a keeper plate 58 secured in position by vertical bolts 59 passed through the keeper and secured in lugs formed on the pan 56. A keeper plate 58 is provided with a drainage neck 60 having connection with a drainage valve 61 attached to the lower end thereof.

With the injector tube entered into the stomach, the forward part 13 of the table is inclined downwardly as shown in dotted lines in Figure 1 and upon manipulation of the valve 31 together with the valves leading from the containers, the liquid to be injected will flow by gravity to treat the affected region by reason of the downward inclination of the body of the patient. When it is desired to remove the treating liquid from the intestinal tract, the valves leading from the containers are closed and the valve 31 manipulated to establish communication through the valve between the tube 42 and the tube 41. By reason of the fact that the tube 41 has its terminal disposed below the body of the patient, a head of liquid will be set up in the tube 41 establishing a siphon action which will completely evacuate the liquid.

I claim:

1. In a duodenal drainage apparatus, a patient supporting table, means for inclining the forward portion of said table downwardly, a swinging bracket carried by said table, a valve supported in said bracket, means for supplying a flow of medicated liquid through said valve, means associated with said valve for intestinal injection of liquids passed therethrough into the body of a patient disposed on said table, the forward portion of said table being hinged to incline below the horizontal, a screw secured to the hinged portion for lowering the same to secure gravitational flow of the liquids in the intestines, and means controlled by said valve for evacuation of the liquid from the intestines.

2. In a duodenal drainage apparatus, a table, a bracket carried by said table, a valve mounted in said bracket, means controlled by said valve for intestinal injection of liquids into the body of a patient disposed on said table, means for progressively inclining a portion of said table to cause gravitational flow of the liquid through portions of the intestines, and means controlled by said valve for evacuating the liquid from the intestines.

3. In a duodenal drainage apparatus, a table, a bracket carried by said table, a valve supported in said bracket, means for supplying a flow of medicated liquid to said valve, means controlled by said valve for injecting liquid passed through said valve into the in-

testines of a patient disposed on said table, means on said table for effecting a step by step inclination of one end thereof to incline the body of the patient to promote flow of liquid in the intestines by gravity, and a means controlled by said valve for evacuating the liquid from the intestines.

OSCAR BOTO SCHELLBERG.
